Attorney, Agent, or Firm—George H. Baldwin

[57] CLAIM

The ornamental design for combined charcoal starter and grill or the like, substantially as shown and described.

DESCRIPTION

FIG. 1 is a side elevational view of a combined charcoal starter and grill showing my new design;

FIG. 2 is a front elevational view thereof;

FIG. 3 is a rear elevational view thereof;

FIG. 4 is a top plan view thereof, showing the upper removable grill;

FIG. 5 is a bottom view thereof, showing the slidably removable charcoal support partially broken away; and

FIG. 6 is a cross-sectional view on an enlarged scale taken along line 6—6 of FIG. 1.
